UNITED STATES PATENT OFFICE.

JOHN W. CLARK, JR., OF PROVO, UTAH.

RAILWAY-TIE.

1,070,411.

Specification of Letters Patent. Patented Aug. 19, 1913.

Application filed January 27, 1911. Serial No. 605,081.

To all whom it may concern:

Be it known that I, JOHN W. CLARK, Jr., residing at Provo, in the county of Utah and State of Utah, have invented certain new and useful Improvements in Railway-Ties; and I do hereby declare the following to be a full, clear, and exact description of the same, reference being had to the accompanying drawings, forming a part of this specification, and to the figures and letters of reference marked thereon.

This invention relates to railway ties and has for its object to provide a metal tie with which the use of wood or its equivalent may be greatly economized, the strength of the tie increased, and the advantages incident to the use of wooden ties, in so far as resiliency and adaptability for the insertion of rail fastenings, be secured.

20 The invention consists primarily in a railway tie having a metal body provided at its ends with chambers for the reception of blocks or sections of wood or equivalent material and with recesses or openings in 25 which the rails may be seated directly upon the wood.

The invention further consists in a tie of the character mentioned formed in sections which are loosely or pivotally connected 30 together in such manner that the ends may drop independently so as to seat firmly upon the underlying road bed without displacing or tilting the opposite end, whereby the rails may be maintained in more accurate alignment and buckling prevented.

35 The invention further consists in certain novel details of construction and combination and arrangements of parts, all as will be now described and pointed out particularly in the appended claims.

40 Referring to the accompanying drawings,—Figure 1 is a perspective view of a tie embodying the present improvements, one of the chamber closing end plates being removed; Fig. 2 is a similar view of a slightly modified construction, with both of the end plates in place; Fig. 3 is a detail perspective view of a form of loose connection between the ends of the tie which may 45 be employed in lieu of that shown in Fig. 1; and Figs. 4, 5 and 6 are sectional views in 50 transverse planes through the end chambers of ties having different cross sectional shapes.

55 Like letters of reference in the several figures indicate the same parts.

The body of the tie embodying the present improvements is preferably formed up of sheet or plate metal with a substantially flat bottom portion A and sides B forming 60 a trough-like structure which may be of less height at the center than at the ends. At the ends the trough-like structure is adapted to receive blocks C of wood, fiber or equivalent material which will substantially fill 65 the ends of the trough-like body of the tie and be held firmly in place therein by the sides of the trough and by overlying and end portions to be now described.

The rails are adapted to seat directly upon 70 the blocks C, and in order to permit of this the sides of the trough are cut away, at points b corresponding to the bases of the rails, thus forming shoulders on the metal which will prevent lateral displacement of 75 the rails. To give additional strength, the upper edges of the trough-like body B are bent over the top of the blocks C as at B', and at the inner ends of the blocks an angle iron or plate D is provided for completely 80 inclosing said ends of the chambers, it being understood that the angle irons D are preferably united to the sides and bottom of the trough-like body so as to form a rigid structure. The outer ends of the chambers 85 thus formed are open for the ready insertion and removal of the blocks C, but in use, said outer ends are intended to be closed by removable end angle iron cover plates E which may be conveniently held in place by a 90 tongue e adapted to enter an opening or slot e' and a top E' adapted to overlie the block between the flanges B' and be secured by a spike driven into the block through an opening e². With this construction of tie the 95 rails may be held in place by ordinary spikes inserted or driven through slots or recesses in the edges of the plates D and E', whereby the tie will be adapted for use in the ordinary manner, with the advantage that when worn on one side, the blocks may be 100 reversed in their chambers. Unless badly rotted, the blocks will last practically twice as long as they would if not reversible.

In the preferred construction, the trough-like body of the tie is made in two sections which are so connected together that they will be held against relatively longitudinal movement or independent upward movement at either end, but will be free to drop at 110 either end or rise at the center should the conformation of the road bed be such as to

necessitate this end, when in course of construction or during the passage of loads over the railway.

Conveniently, the connection between the two sections of a tie is in the form of a hinge or pivotal connection known as a rule joint. As shown in Fig. 1 the joint is formed by bearings F, F' on the two sections through which a bolt or pintle f may be passed, as will be readily understood, while shoulders f' limit the pivotal movement in one direction, as shown in Fig. 1. As a modification of the form of joint shown in Fig. 1, that shown in Fig. 3 may be adopted, the end of one section being telescoped into the end of the other section, and the side walls B connected by a transverse bolt G, the arrangement of the parts being such as to permit of the movements described in connection with Fig. 1. The bottom of the outer section may be cut away below the bolt sufficiently to permit either end to swing downwardly and the end of the inner section form the stop to prevent upward swinging movement.

In Fig. 2 the tie is shown rigid from end to end, and in this instance the chambers for the blocks C are formed integral with the body of the tie itself, as shown at H, this result being secured by welding or by bending up the metal as will be understood by those skilled in the art.

Obviously, the form of the opening left in the top of the end chambers for the reception of the bases of the rails may be made to conform to any rail which it may be desired to use; thus, as shown at the left end of Figs. 1 and 2, one side of the opening is substantially straight while the other side is curved, so as to receive a rail base having on one side a curved conformation which will give additional rigidity to the rail, and lock the rail and tie together against relative longitudinal movement without increasing the strain on the retaining spikes or fastenings.

While in Figs. 1 and 2 the cross sectional shape of the chambers at the ends of the tie is substantially rectangular it will be understood that said chambers may be of any preferred or desired shape in cross section; thus, as shown in Fig. 4, the cross section is in the form of a trapezoid, the two side walls I inclining inwardly from the base. In Fig. 5 the end chambers are of semi-cylindrical form, the top surface being curved as at K, and, in this instance where additional bearing surface for the rail is desired, the block may be cut down as indicated by the dotted line k. In Fig. 6, the cross sectional shape is rectangular but the side walls L are located a much greater distance apart than in Figs. 1 and 2, and the top plate l is held beneath the overlying shoulders or flanges l' of the side walls L.

In all of the illustrations it will be under-

stood that the rail seats directly upon the wooden blocks held in the chambers at the ends of the tie, and in the preferred construction the pressure is transmitted downwardly through the said blocks to the bottom plate of the tie. In other words, the side walls of the tie are relieved of downward pressure from the rail base, by being cut away on each side at b, as before explained.

While the spikes holding the rails to the blocks will afford all of the strength which is usually secured by such fastening devices, the present invention contemplates the utilization of the shoulders formed by the side walls on each side of the rail opening as a means whereby lateral movement of the rails will be effectually prevented even though there should be some looseness between the ends of the block and the ends of the chambers.

In lieu of wooden blocks it will be understood that the invention contemplates the use of blocks of other material, such for instance, as fiber or compressed paper, and it will be understood in the claims that where a wooden block is specified such other material is considered as the full equivalent thereof.

In laying tracks, long ties extending across from rail to rail, may be alternated with short chamber sections with their contained blocks under each rail.

Having thus described my invention, what I claim and desire to secure by Letters Patent of the United States, is:

1. A metal railway tie body formed of sheet metal with a flat base and upturned sides constituting a trough like structure, the end portions of said sides being bent inwardly to form chambers for the reception of wooden blocks, and angle iron plates for closing the ends of the chambers and overlying the blocks between the inturned portions of the sides, said plates being provided with openings for the reception of spikes for holding both the plates and rails on the block.

2. A metal tie for railways formed of sheet metal with a substantially flat bottom, upwardly extending side walls of greater height at the ends than at the center, the end portions of said side walls being turned inwardly to form chambers for the reception of wooden blocks, said chambers each having a transverse opening in the top of the same for the reception of the rail bases, and the ends of said flanges adjacent said openings forming shoulders for limiting the lateral movement of the rails and angle plates for closing the ends of the chambers and overlying the blocks between the inturned portions of the sides of the tie.

3. A metal tie for railways embodying a trough like body portion, upwardly extend-

ing sides and inturned flanges at the upper edges of the sides forming chambers for the reception of wooden blocks, said chambers each having a transverse opening in 5 the top of the same for the reception of the rail bases, the ends of the flanges adjacent said openings forming shoulders for limiting the lateral movement of the rails, an angle plate for permanently covering one 10 end of the chamber and extending over the top of the block between the flanges to the transverse opening, and a removable angle plate for closing the opposite end of the chamber and extending over the top of the 15 block between the flanges to the transverse

opening and means for holding the rail and plate on the block.

4. A metal railway tie for railways formed of sheet metal with a flat base and upturned sides constituting a trough like 20 structure, the end portions of said sides being bent inwardly to form chambers for the reception of wooden blocks, and angle iron plates for closing the ends of the chambers and overlying the blocks between the in- 25 turned portions of the sides.
